UNITED STATES PATENT OFFICE.

CHARLES DAVID BONSALL, OF CHICAGO, ILLINOIS, ASSIGNOR TO UNION METAL PRODUCTS COMPANY, OF CHICAGO, ILLINOIS, A CORPORATION OF DELAWARE.

PANELING FOR HOPPER DOORS FOR RAILWAY CARS.

Application filed August 17, 1925. Serial No. 50,871.

The invention relates to a railway dump car having a "door" forming a part of the car for retaining the load therein, which door is provided with hinges adjacent one 5 of its sides and is capable of being "dropped" or swung open so that the load in discharging slides or passes over the upper surface of the door. Any means of raising the door to the closed position, and 10 any means for locking and releasing the door, may be employed with my device. A door for this purpose must be very strong and durable because:

First. It is part of the floor of the car 15 and as such must sustain the load as well as the impact blow when the car is in motion.

Second. The car is frequently loaded from chutes or tipples from a height of 20 ten feet or more, causing the load to be dropped directly upon the doors.

Third. Clam shell buckets are frequently used to unload such cars and it is not uncommon for these buckets to rest upon and 25 drag over the doors.

Fourth. When the door suddenly comes to rest after being dropped it is not only subject to a severe shock but it must sustain the severe impact thrust of the load 30 which, of course, follows the door.

Fifth. As the load is theoretically equally distributed, the door must be strong over its entire area and must be capable of transmitting the resulting strains to the car body 35 without much deflection and no substantial distortion.

Any bending of the door or dropping of the corners would cause a leak of the lading, especially of such fine material as sand, 40 chaffs, etc. Any bending or warping might interfere with the complete closing and locking of the door.

As it costs as much to haul a ton of car as it does to haul a ton of paying freight, 45 it is imperative that the car and any part thereof be as light as possible. Furthermore, the total weight of car and freight is determined by the strength of certain standard axles so that the lighter the car the 50 greater amount of freight a given car will be allowed to carry. With my arrangement I obtain a strong, light and inexpensive door.

In the drawings:

Fig. 1 shows a door formed according to 55 my invention.

Fig. 2 is a section on line 2—2 of Fig. 1.

Fig. 3 is a section on line 2—2 of Fig. 1 showing a modification.

Fig. 4 is a section on line 4—4 of Fig. 1 60 showing the hinge relation.

Fig. 5 is a section on line 4—4 of Fig. 1 showing the hinge relation to a modified form.

Any number of panels may be used of 65 various depths, position and shape and still come within the scope of this invention.

In Fig. 2 numeral 7 is the side walls of a panel pressed from the main portion 6 of the plate. Numeral 8 is the side walls 70 of a panel pressed from the elevated portion of the first mentioned panel and numeral 9 is the side walls of a panel pressed from the elevated portion of the last mentioned panel. Margins 10 and 11 are thus 75 formed between panel within panel.

The margins 13 and 14 at the sides of the door are wider than the margins 6, 10 and 11 at the ends of the door. The walls 7, 8 80 and 9, parallel to the ends of the door, are then closer together than the walls 16, 17 and 18, parallel to the sides of the door.

In some cars the hoppers are narrower at the bottom than at the top of the door opening and the door is made substantially 85 the same shape as the hopper opening. It is preferable to have the embossed panels conform to the shape of the door, or at least, approximately so, as illustrated.

In Fig. 3, 7' is the side walls of a panel 90 pressed from the main portion 6 of the plate. Numeral 8' is the side walls of a panel pressed from the portion of the first mentioned panel in an opposite direction thereto leaving flat margins 10' and numeral 95 9' is the side walls of a panel pressed from the elevated portion of the last mentioned panel and in the same direction leaving flat margins 11'. The panel 12 of the last mentioned embossment is in substantially the 100 same plane as the main portion 6 of the plate.

Figs. 4 and 5 show the relation of the hinge 20 to the body of the door. The hinge 105 spans the embossed panel and is secured (22) to the margin on the opposite sides of a

panel, thus increasing the strength of the embossed plate by tying the opposite portions of the margin together. A strut 21 may be inserted between the hinge and the embossed panel and be secured thereto (23-24).

In such an arrangement the panel and hinge are the compression and tension members, respectively, of a truss.

10 I claim:

1. A plate metal door for a railway car having an embossed panel pressed from the plane of the plate with flat margins surrounding said panel, and an embossed panel 15 pressed from the first mentioned panel with flat margins surrounding the last mentioned panel, the margins at the sides of the panels being narrower than the margins at the ends of the panels.

20 2. A plate metal door for a railway car having an embossed panel pressed from the plane of the plate with flat margins surrounding said panel, and an embossed panel 25 pressed from the first mentioned panel with flat margins surrounding the last mentioned panel, said embossed panels projecting in the same direction, the margins at the sides of the panels being narrower than the margins at the ends of the panels.

25 3. A plate metal door for a railway car having an embossed panel pressed from the plane of the plate with flat margins surrounding said panel, and an embossed panel 30 pressed from the first mentioned panel with flat margins surrounding the last mentioned panel, said embossed panels varying in depth, the margins at the sides of the panels being narrower than the margins at the ends of the panels.

4. A plate metal door for a railway car 40 having an embossed panel pressed from the plane of the plate with flat margins surrounding said panel, and an embossed panel pressed from the first mentioned panel with flat margins surrounding the last mentioned 45 panel, said embossed panels projecting in the same direction, and varying in depth, the margins at the sides of the panels being narrower than the margins at the ends of the panels.

5. The combination of a plate metal door 50 for a railway car having a panel pressed from the plane of the plate with a margin surrounding the panel, and a hinge spanning said panel and secured to said margin on the opposite sides of said panel.

6. The combination of a plate metal door 55 for a railway car having a panel pressed from the plane of the plate with a margin surrounding the panel, a hinge spanning 60 said panel and secured to said margin on the opposite sides of said panel, and a strut positioned between and secured to said panel and said hinge.

7. In combination with the other elements 65 of a railway dump car, a plate metal door having a succession of panels, each formed consecutively within another panel forming flat margins between the panels.

8. In combination with the other elements 70 of a railway dump car, a plate metal door having a succession of panels, each formed consecutively within another panel forming flat margins between the panels with the margins on opposite sides of the panels 75 being substantially equal in width.

CHARLES DAVID BONSALL.
